(57) **CLAIM**

We claim the ornamental design for an insect repeller, as shown and described.

DESCRIPTION

FIG. 1 is a front perspective view of an insect repeller of the present invention.

FIG. 2 is a front view of the insect repeller of FIG. 1.

FIG. 3 is a rear view of the insect repeller of FIG. 1.

FIG. 4 is a top view of the insect repeller of FIG. 1.

FIG. 5 is a bottom view of the insect repeller of FIG. 1.

FIG. 6 is a left-side view of the insect repeller of FIG. 1; and,

FIG. 7 is a right-side view of the insect repeller of FIG. 1.
